[57] CLAIM

The ornamental design for a beach wagon, as shown and described.

DESCRIPTION

FIG. 1 is a right side elevational view of a beach wagon showing my new design, with the foldable pulling handle thereof in the folded position and the upper two of four foldable hooks on the right side thereof shown in the unfolded positions thereof;

FIG. 2 is a front elevational view thereof, with the left side fold-down table thereof shown in the folded-down position thereof;

FIG. 3 is a top plan view thereof, with the handle thereof shown in the unfolded position thereof;

FIG. 4 is a left side elevational view thereof, with the fold-down table thereof shown in the folded-up position thereof;

FIG. 5 is a rear elevational view thereof;

FIG. 6 is a bottom plan view thereof;

FIG. 7 is a longitudinal vertical cross-sectional view thereof on line 7—7 of FIG. 2;

FIG. 8 is a transverse vertical cross-sectional view thereof on line 8—8 of FIG. 1; and,

FIG. 9 is a horizontal cross-sectional view thereof on line 9—9 of FIG. 1.

FIG. 1

FIG. 2

FIG. 3

FIG. 6

FIG. 7

FIG. 8

FIG. 9
